US0D1083665S

(12) United States Design Patent (10) Patent No.: US D1,083,665 S
(45) Date of Patent: * Jul. 15, 2025

(54) BUCKLE

(71) Applicant: TOD'S S.p.A., Sant'Elpidio a Mare (IT)

(72) Inventors: Diego Della Valle, Sant'Elpidio a Mare (IT); Lucia Occhioni, Sant'Elpidio a Mare (IT)

() Term: 15 Years

(21) Appl. No.: 35/522,081

(22) Filed: Aug. 17, 2023

(80) Hague Agreement Data

Int. Filing Date: Aug. 17, 2023

Int. Reg. No.: DM/232284

Int. Reg. Date: Aug. 17, 2023

Int. Reg. Pub. Date: Aug. 23, 2024

(30) Foreign Application Priority Data

Feb. 23, 2023 (EM) 015012398-0002

(51) LOC (15) Cl. 02-07

(52) U.S. Cl.

USPC D11/200
